UNITED STATES PATENT OFFICE.

NAPOLEON DU BRUL, OF CINCINNATI, OHIO.

DESIGN FOR A CAM.

SPECIFICATION forming part of Design No. 34,513, dated May 14, 1901.

Application filed April 8, 1901. Serial No. 54,953. Term of patent 14 years.

To all whom it may concern:

Be it known that I, NAPOLEON DU BRUL, a citizen of the United States, and a resident of Cincinnati, county of Hamilton, State of Ohio, have invented and produced a new and original Design for a Cam, of which the following description, taken in connection with the accompanying drawings, is a specification.

My new design is illustrated in the accompanying drawings, in which—

Figures 1 and 2 are views of diametrically opposite sides of a cam. Fig. 3 is a view of the right-hand end of Fig. 1 and the left-hand end of Fig. 2, and Fig. 4 is an axial section in the plane of Fig. 2.

The essential features of my new design are a central cylindrical body having an axial opening, a surrounding flange with the planes

of its faces spirally or angularly arranged with relation to the axis of the body, and a larger surrounding flange, the faces of which are also arranged spirally or angularly with relation to the axis of the body and having in one of its faces an axially-presented groove for the most part concentric with the axis of the body and with an approximately flattened portion depressed toward said axis.

Having thus described my invention, what I claim as new, and desire to secure by Letters Patent, is—

The design for a cam substantially as herein shown and described.

NAPOLEON DU BRUL.
